UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

PROCESS OF TREATING METAL.

Application filed August 30, 1920. Serial No. 406,922.

To all whom it may concern:

Be it known that I, WILLIAM G. Hous-
keeper, a citizen of the United States,
residing at New York, in the county of
5 New York and State of New York, have
invented certain new and useful Improve-
ments in Processes of Treating Metal, of
which the following is a full, clear, concise,
and exact description.

10 This invention relates to a process of
treating metal and has particular reference
to a process in which metal is treated to high
heat in a vacuum.

The object of the invention is to provide
15 a simple, efficient, and economical process
whereby in the preparation of metallic and
other parts of devices such, for example as
the metallic and other parts of thermionic
discharge devices, the metal and other por-
20 tions are thoroughly cleaned and rid of
vapours and gases contained therein and
are handled to a minimum degree after
treatment and before assembly in their
ultimate positions in the devices with which
25 they are used. While I have cited thermi-
onic discharge devices, it is to be clearly
understood that the invention is useful in
other situations in which the same require-
30 ments are to be fulfilled, such as the prepa-
ration of metal for chemical analysis, the
preparation of metal to be used in any
laboratory experiments where freedom from
dirt and gas and vapour is desirable.

The invention in general comprises the
35 following steps:

1. The manufacture in complete or partly
complete form of the metal and other parts
to be treated so that after treatment a mini-
40 mum amount of handling is required to com-
plete the assembly;

2. The introduction of the metal and other
part or parts into an oven, preferably, al-
though not necessarily an electric oven.

3. The treatment of the metal and other
45 parts in the oven to high temperature, of
the order of 1100 degrees C. for several
hours while the interior of the oven is
evacuated to a high degree.

This process is related to the process set
50 forth in Patent No. 1,456,523, May 29, 1923,
"method of treating metals" in the name of
Russel F. Trimble.

The invention is illustrated in the draw-
55 ing, of which Fig. 1 represents a longitudi-
nal section, with some parts in elevation, of

an electric oven which is used to carry out
a step in the process; Fig. 2 represents a
thermionic discharge device the metallic
parts of which can be treated in accordance
with the process.

As shown in the drawing, with reference
to Fig. 1, the electric oven which is prefer-
ably, although not necessarily, used in the
carrying out of the process comprises an
outer container 1, and an inner receptacle 2,
60 which are spaced apart. The outer con-
tainer is provided with inlet and outlet
ports 3 and 4 respectively for the circulation
of a cooling medium around the inner re-
ceptacle. Within the inner receptacle is a
65 heater tube 5 of refractory material around
which is wound an electrical heater wire 6.
This wire is connected to contact plates 7
and 8 with which terminals 9 and 10 are
adapted to make contact. These terminals
70 are carried by an insulating plate 11 prefer-
ably of heat resisting glass which is adapted
to rest on a flange 12 of a metallic cap 13
for the upper end of the inner receptacle
2. Circuit wires 14 and 15 connect the ter-
75 minals 9 and 10 with any suitable source
of power. Within the receptacles 2 and
around the heater tube 5 is positioned a plu-
rality of highly polished reflecting surfaces
16, 17 and 18. These surfaces are preferably
80 formed of cylindrical nickel sheets polished
on both sides. The charge for the oven is
placed within the heater tube 5 and rests
upon a support 19 comprised of a plurality
85 of highly polished nickel plates. Above the
charge is placed another similar set of
highly polished plates 20. For a more de-
tailed description of the structure of the
oven reference may be had to a co-pending
90 application filed August 24, 1920, Serial 95
Number 405,768, "electrical heating ovens"
in the name of M. J. Kelly and T. R.
Griffith. The vacuum within the receptacle
2 is produced by connecting the pipe 21 with
95 a vacuum pump.

In Fig. 2 is shown a thermionic discharge
device, the treatment of the metal and other
parts of which forms an example of the op-
eration of my process. This device com-
prises an evacuated vessel 30 having a stem
31 of glass. Above the stem 31 is located a
framework comprising a pair of blocks 32
and 33 of insulating material such as
"lavite," a commercial form of steatite,
which are to be treated and which are con-
100
105
110

nected and spaced by means of a pair of rods 34 and 35 of nickel. An anode or plate electrode 36 is welded along its edges to the rods 34 and 35. A spiral grid or control electrode 37 is supported within the anode 36 from wires such as 38. A cathode or filament 39 is supported within the grid 37 and the anode 36 by wires such as 40. For a detail description of this thermionic discharge device reference may be had to a co-pending application filed July 20, 1920, Serial Number 397,764, in the name of William G. Houskeeper. The frame above described, together with the electrodes, is supported from the stem 31 by means of angle bars 41 and 42 which are welded at their upper ends to the anode 36 and at their lower ends are fastened, viz, welded, to a collar 43 which surrounds the stem 31.

In carrying out the process of this invention, if the framework and the electrodes with the supporting bars and collar are composed of highly refractory material, they may be completely assembled ready for mounting on the stem 31. For instance, the collar 43, the bars 41 and 42, and the anode 36 may be all welded together as a unit. To this unit may be added the rods 34 and 35, the blocks 32 and 33 and the grid 37 with its supporting wires 38. It is desirable that the electrode unit, including the frame-work, be treated to a high temperature in a vacuum to rid it of vapors, gas, and volatizable impurities which may reside therein, so that when later assembled in the vessel 30 and in actual operation, these parts will not emit vapor and gas which would interfere with the proper operation of the tube as an amplifier by causing positive ionization. It has been found that if the material in sheet form, or other form in which it is to be had on the market, is treated to eliminate the impurities above referred to, the subsequent processes of stamping, forming and welding the material to form the completed article, and the great amount of handling necessary in these processes, cause the electrodes and other parts to acquire volatizable impurities, such as oil or grease. This is avoided by treating the unit at a suitable temperature in a suitable vacuum oven such as the one above described. With highly refractory materials, a temperature of 1100 or 1200 degrees centigrade may be obtained

and maintained for one-half to three hours 55 at a pressure of the order of 10^{-8} mm. of mercury.

Where some of the elements are of less refractory materials, a somewhat different process covered by the above mentioned 60 Trimble application is employed. For example, the grids and plates are frequently made of nickel and are not capable of withstanding the high temperatures to which the "lavite" blocks may be subjected. If the 65 filaments are made of oxide coated platinum, it is not desirable to treat them in the oven at all, since the small amount of impurities contained in the filament may be removed during the pumping of the vacuum tube. In this case, the manufacture of each 70 electrode and associated parts is carried as far as possible before the complete assembly of the unit. The "lavite" blocks, after having been shaped and drilled, are treated in 75 the oven separately at a temperature of 1100 to 1200 degrees centigrade. The grids and plates are reduced to their final form ready for assembly and are treated at a temperature of about 950 degrees centigrade. The 80 complete unit is then assembled as above described, and can be placed in the tube without having acquired any considerable amount of impurities.

While three hours have been stated to be 85 a suitable period for treating a considerable quantity of material, this period will, of course, vary with the kind and amount of material to be treated.

It is understood further that the details 90 of the various steps may be varied without departing from the spirit of the invention as set forth in the following claims.

What is claimed is:

The process of manufacturing electron 95 discharge devices which comprises stamping and forming electrodes from untreated metal, subjecting the formed electrodes to a high temperature in vacuum, assembling said electrodes within an enclosing vessel, evacuating said vessel and simultaneously heating said electrodes, and sealing off said vessel.

In witness whereof, I hereunto subscribe my name this 23rd day of August A. D., 105 1920.

WILLIAM G. HOUSKEEPER.
